TIMING APPARATUS

Rodney G. Richardson, Chicago, Ill., assignor to
 George W. Borg Corporation, Chicago, Ill., a
 corporation of Delaware

Application February 23, 1943, Serial No. 476,839

8 Claims. (Cl. 73—6)

The present invention relates in general to timing apparatus, and more in particular to stroboscopic timing apparatus suitable for use in timing watches. The object of the invention is to produce a new and improved apparatus of this character.

A well known stroboscopic watch timer is shown in the patent to Gibbs, No. 2,303,540, granted December 1, 1942. The watch timer disclosed in this patent comprises a calibrated dial rotated at a constant speed bearing a predetermined relation to the beat frequency of the watch to be timed and a lamp or lamps for intermittently illuminating the dial calibrations in response to the beats of the watch. A modification of this apparatus uses a dial with an opening or indicator therein, as disclosed in the Young Patent No. 1,953,148, together with a fixed calibrated scale with which the opening in the dial cooperates when illuminated in response to watch beats.

The above described watch timing apparatus utilizes all the beats of the watch undergoing test; that is, the lamp is flashed in response to each watch beat. This feature gives rise to an objection in the case of watches which do not beat evenly, as such watches exhibit a vibratory indication on the timing apparatus, due to the difference in the time interval between alternate beats. A steady indication is generally to be preferred.

The above indicated problem is recognized in the patent to Norman, No. 2,064,559, which discloses a stroboscopic type of watch timer which uses only half the beats of the watch being timed. This result is secured by means of a commutator arrangement, whereby only the odd (or even) beats of a watch are made effective to flash the lamps.

To a certain extent the present invention is directed to the same problem. It affords a more complete solution, however, in that both the odd and even series of watch beats are used, and are timed separately. One indication is obtained in response to the odd numbered beats and a separation indication is obtained in response to the even numbered beats. Both indications are steady or non-vibratory, and either may be used for timing purposes.

The great advantage of the invention, however, lies in the fact that the desired result is obtained without the use of any commutator or equivalent switching arrangement. I have discovered that the problem can be solved by selecting a dial speed which bears a particular relation to the watch beat frequency and by providing two

scales located in specified angular relation to each other, together with dial openings the number and location of which bear the proper relation to the other factors involved.

5 A special advantage of the invention lies in the fact that an apparatus constructed in accordance therewith, although designed especially for timing five-beat watches, may also be used for timing six-beat watches.

10 According to another feature of the invention a new and improved arrangement is provided for bringing the rotating dial into phase with the watch beats at the beginning of a timing operation.

15 The invention and the various features thereof will be fully described hereinafter, reference being made to the accompanying drawing, in which:

Fig. 1 is a front view of a watch timing apparatus embodying the invention;

Fig. 2 is a side view of the same apparatus;

Fig. 3 is a detail of a part of the phase adjusting mechanism;

Figs. 4 and 5 are block diagrams of the electrical circuits involved; and

Figs. 6 and 7 are front views similar to Fig. 1, but showing modified forms of the invention.

Referring to the drawing, the various parts of the timing apparatus are mounted on a suitable 30 base 10, which may be of rectangular shape and of any suitable material. At the front of the base there is provided an upright panel 11, having the two arcuate windows 12 and 13. Associated with the windows 12 and 13, respectively, 35 are the two fixed scales 14 and 15.

Behind the panel 11 there is a rotatable dial 16 having a single diamond-shaped opening or indicator 20 therein. This opening, when illuminated by lamp flashes during the timing of a 40 watch, serves as an index or pointer and cooperates with the scales 14 and 15.

The dial 16 is mounted on the shaft 17, which is supported in bearings in the brackets 18 and 19. The bracket 19 is secured to bracket 18 and the latter is attached to the base 10, as indicated. The bracket 18 also supports the two neon lamps 21 and 22 which are located opposite the windows 12 and 13, respectively.

The reference character 25 indicates the driving motor for the dial, which is mounted on the base 10 by means of a suitable supporting bracket 26. The motor may be a split phase synchronous motor.

The motor 25 drives the dial 16 through the medium of the bevel gears 28, 29 and 30. The

gears 28 and 30 are fixed on the motor shaft 27 and the dial shaft 17, respectively, while the gear 29 is rotatably supported on the large spur gear 31. The latter gear is rotatably supported on the shafts 17 and 27 as indicated, or it may be supported on one of these shafts alone, which is made somewhat longer for this purpose.

Fig. 3 shows how the gear 29 is mounted on the gear 31. A portion of the gear 31 is cut out and in the space thus provided the gear 29 is rotatably supported on the pin 32.

The reference character 33 indicates a shaft which passes through the front panel 11 and is also supported in bearings in the extensions 35 and 36 of brackets 13 and 26, respectively. In front of the panel 16 there is a knob 34 fixed to shaft 33. A pinion 38 is fixed to shaft 33 and is in mesh with the spur gear 31. The pinion 38 also meshes with an internally toothed sector 39, fixed to the base 10, whereby the pinion 38 and gear 31 are normally prevented from rotating. The shaft 33 may, however, be moved to the left against the tension of spring 31 to disengage the pinion 38 from sector 39, whereupon the shaft and pinion can be rotated to rotate the gear 31. The knob 34 is used to manipulate the shaft 33 as described here, for the purpose of adjusting the phase relation between the dial and the beats of the watch being tested.

The usual way of accomplishing the foregoing is to provide a rotatable mounting for the motor, together with means whereby the whole motor may be rotated in either direction about an axis coinciding with the motor shaft. There are obvious objections to this construction, which are overcome by the arrangement disclosed herein.

A satisfactory arrangement for supplying the power for running the motor 25 is diagrammatically shown in Fig. 4, and is disclosed in Patent No. 2,304,813, granted December 15, 1942.

This equipment may be referred to as a standard frequency generator, and comprises a standard frequency source which is preferably a crystal oscillator, a frequency divider comprising several multivibrator stages, and some kind of power amplifier. A single stage push-pull amplifier may be used, for example. The standard frequency generator must have the proper output frequency to run the motor at the required speed. The motor speed is $7\frac{1}{2}$ R. P. S., or 450 R. P. M. A 16-pole motor may be used, in which case the output frequency should be 60 cycles per second.

The arrangement for flashing the lamps 21 and 22 responsive to watch beats is diagrammatically illustrated in Fig. 5 and comprises a pick-up or microphone for generating electrical impulses responsive to watch beats or ticks, a tick amplifier, and means such as a thyratron for converting the amplifier output into extremely short direct current impulses corresponding in frequency to the watch beat frequency. These impulses are used to flash the lamps 21 and 22. The complete circuits of an arrangement such as described are shown in Patent No. 2,303,540 previously referred to.

The apparatus having been described, its operation will now be explained briefly, it being assumed for this purpose that the motor 25 is connected up as shown in Fig. 4, and that the lamps 21 and 22 are connected as shown in Fig. 5. The motor runs at a speed of $7\frac{1}{2}$ R. P. S. and rotates the dial 16 at the same speed. The dial may rotate in either direction, but clockwise rotation as viewed from in front of panel 11 will be assumed.

A watch to be timed may now be placed on the pick-up device as shown in Fig. 5, with the result that the lamps 21 and 22 start flashing in synchronism with the watch beats. Lamp 21 illuminates the dial opening or indicator 20 and renders it visible at the window 12, provided a flash occurs during the interval in which the indicator is passing the window, and lamp 22 functions in the same way with respect to the window 13.

When the first lamp flash occurs the indicator 20 may be passing the window 12 and will appear to be stationary at some point in the window due to the very short duration of the lamp flash. Then when the next flash occurs the indicator will be passing the window 13 and will be seen at a point directly opposite, or 180 degrees from the point where it first appeared. Or the first lamp flash may illuminate the indicator 20 at window 13, in which case the second flash will illuminate it at window 12. Thus one-half of the lamp flashes, the odd flashes, for example, will occur while the indicator is at window 12, and the even flashes will occur while the indicator is at window 13.

It will be appreciated, of course, that when the lamps start to flash the indicator 20 may be somewhere between the two windows and will not be visible. To bring the indicator into view, the operator uses the phase-adjusting mechanism, by means of which the dial is rotated with respect to the motor and is brought into the proper phase relation with the watch beats. This operation will be explained presently.

The reason why the indicator 20 appears at windows 12 and 13 alternately will now be explained briefly.

As previously mentioned, the dial speed is 450 R. P. M., or $7\frac{1}{2}$ R. P. S. The dial speed in degrees per second is therefore equal to the product of 360 and $7\frac{1}{2}$, or 2700 degrees per second. The beat frequency of the watch being tested is 5 beats per second. Dividing 2700 by 5, we obtain the quotient 540, which is the dial speed in degrees per watch beat.

Now we may assume that when the lamps flash in response to some particular watch beat the indicator 20 appears at zero on the scale associated with window 12, as shown in Fig. 1. Then when the next flash occurs the dial 16 will have rotated 540 degrees, which is equal to 360 degrees plus 180 degrees, or to $1\frac{1}{2}$ rotations of the dial, and the indicator 20 will appear at a point 180 degrees in advance of the point where it appeared on the previous lamp flash, or at zero on the scale associated with window 13. The two zeros are 180 degrees apart. When the next or third flash occurs the dial will have rotated another 540 degrees, or $1\frac{1}{2}$ rotations, and the indicator 20 will appear at zero, window 12, where it appeared on the first flash. When the fourth flash occurs the indicator 20 will appear at zero, window 13, again, and at the fifth flash it will again appear at zero, window 12, as will be readily understood. Running at a speed of 540 degrees per beat the dial gains 180 degrees at each beat. In whatever position the indicator 20 may be on the first beat, therefore, on the second beat it will be in a position 180 degrees in advance of its first position, and on the third beat the dial will have gained twice 180 degrees, or 360 degrees, and the indicator will have returned to its initial starting position.

That the indicator will appear at points 180 degrees apart on any two successive beats may be

demonstrated by the fact that the numbers which measure the total angular distance through which the dial rotates in n beats and in $n+1$ beats are, respectively, evenly divisible by 360 and divisible by 360 with a remainder of 180, or vice versa. Thus in 10 beats the dial rotates through an angular distance of 5400 degrees. The number 5400 is evenly divisible by 360, the quotient being 15. In 11 beats the angular distance rotated is 5940 degrees. The number 360 goes into the number 5940 16 times, with a remainder of 180.

At the beginning of the timing operation the indicator 20 will appear at some random point on the scale associated with window 12, also at a point diametrically opposite on the scale associated with window 13. Or the indicator may not be visible at all, as previously mentioned. In any event the operator will first proceed to bring the indicator in phase with the watch beats. In order to accomplish this the knob 34 is pulled out far enough to disengage the pinion 38 from the sector 39 and the knob is then rotated, thereby rotating the dial with respect to the motor shaft through the medium of pinion 38 and gear 31. This independent rotation of the dial changes the position which the indicator 20 occupies at the times the lamps flash, and the adjustment is continued until the indicator appears at zero on the scale to be used. If the watch is beating evenly it will also appear exactly at zero on the other scale, but only one scale need be used for the timing operation. Having adjusted the indicator to zero, the operator will restore the knob 34 and reengage the pinion 38 with the sector 39, which locks the gear 31 in adjusted position.

If the rate of the watch being timed is correct, the indicator 20 will remain stationary; that is, it will continue to appear at zero on the scale, and this fact indicates to the operator that the watch is keeping correct time.

If the watch is slow the intervals between beats or flashes will be longer than normal and the dial will rotate farther between successive beats than it would if the watch were correct, with the result that the indicator will drift along the scale in a clockwise direction. If the watch is fast, on the other hand, the indicator will drift along the scale in the opposite direction.

In practice the timing operation is continued for a definite period such as one minute, for example, and the scale may be calibrated so that the angular distance which the indicator travels from zero during the timing period can be read directly as the error in the rate of the watch in seconds per day.

The timing operation is similar to the timing operations performed with known types of stroboscopic watch timing machines and need not be further described.

Reference may now be made to Fig. 6 and the modification there shown will be described. Only the front panel is shown, since the rest of the apparatus is the same as shown in Figs. 2 to 5, inclusive, except for the location of the lamps 21 and 22.

The front panel, Fig. 6, is provided with two windows 50 and 51, located side by side on the upper half of the panel. Associated with the windows 50 and 51 are the scales 52 and 53, respectively. The zeros on the two scales are 90 degrees apart. The dial has two openings or indicators 54 and 55, which are also separated by 90 degrees. The lamps 21 and 22 are relocated so as to be

opposite the windows 50 and 51, respectively, the bracket 48 being provided with a cross member for supporting the lamps in the proper position, as will be readily understood.

With the apparatus in operation for timing a watch, it will be assumed that the dial has been adjusted as to phase so that the indicator 54 will appear at zero on scale 52, as shown in the drawing. A beat or lamp flash which renders the indicator 54 visible in this position will not render the indicator 55 visible, due to its position 90 degrees behind the indicator 54. When the next flash occurs, the dial will have rotated 540 degrees and the indicator 54 will be in a position directly opposite, or 180 degrees from the position in which it appears in the drawing. In its new position the indicator 54 will not be visible. The indicator 55, however, will have made a net advance of 180 degrees (540 degrees - 360 degrees) and will appear at zero on the scale 53. When the next flash occurs the dial will have gained 180 degrees more and both indicators will be again in the positions in which they are shown. This cycle repeats itself indefinitely. Thus it will be seen that half of the flashes display the indicator 54 at zero, scale 52, while the other half of the flashes display the indicator 55 at zero, scale 53.

The timing operation is the same as previously explained. If the watch is correct, the indicators will remain at zero, but if not, the indicators will drift away from zero in one direction or the other depending on whether the watch is fast or slow.

It should be pointed out that with the arrangement of Fig. 6 the dial may be so adjusted as to phase that when a lamp flash occurs the two indicators 54 and 55 appear at the two zeros, respectively, on scales 53 and 52. With this adjustment, when the next flash occurs the two indicators will be behind the lower half of the panel and will be invisible. When the next flash occurs they will again appear at the two zeros, respectively. Thus half the flashes are utilized to display the indicators simultaneously, while the other half of the flashes are not used at all. The operator can tell which adjustment obtains by noting whether the indicators appear simultaneously or alternately, the flashing rate being slow enough so that this can readily be determined.

Fig. 7 shows another modification which will now be described. This modification, like that of Fig. 6, is characterized mainly by the arrangement of the windows and the indicators on the dial.

There are two concentric windows, an outer window 60 and an inner window 61, each having a scale associated therewith. The dial has two openings or indicators 62 and 63, which are 180 degrees apart. The two indicators are located at different distances from the center of the dial, so that they cooperate with the two concentric windows, respectively. The lamps such as 21 and 22 may be located as described in connection with Fig. 6.

Assuming that the apparatus is in operation, the dial may be adjusted as to phase so that when a lamp flash occurs the indicator 62 will appear at zero on the scale associated with window 60, as shown in the drawing. Then when the next flash occurs the dial will have gained 180 degrees and the indicator 62 will be in a position 180 degrees in advance, where it will be invisible. The indicator 63, however, will also have made a net

advance of 180 degrees and will appear at zero on the scale associated with window 61. When the next flash occurs, the indicators will have assumed their initial positions, indicator 63 being invisible while indicator 62 appears at zero on the scale associated with window 60. Thus half the flashes are effective to display the indicator 62 at window 60 while the other half of the flashes are effective to display the indicator 63 at window 61.

The timing operation is carried out the same as in the two preceding cases and need not be described.

In all of the modifications the alternate beats of a watch are timed separately so that the desired object of obtaining a steady non-vibratory indication is attained, even though the watch being timed does not beat evenly. The disadvantage inherent in those watch timers which use all the beats to produce a single timing indication is thus eliminated. At the same time the advantage of being able to recognize when a watch being tested is not beating evenly is not sacrificed, due to the fact that although the alternate beats are timed separately the separate indications may be compared. When the dial in Fig. 1, for example, is adjusted so that the indicator 20 appears at zero in window 12 the indicator should also appear exactly at zero in window 13, and if it does not the operator is thereby advised that the watch is not beating evenly. The modification Fig. 7 has a special advantage in this connection, due to the fact that the two indicators appear in radial alignment at the two windows if the watch being tested is beating evenly. If the watch is not beating evenly the resulting displacement of one of the indicators can easily be detected. It will be understood that before testing a watch for an even beat it must be regulated as to rate, so that there will be no substantial drift of the indicators between successive beats.

That a six-beat watch can be timed on the apparatus disclosed herein may be shown by calculating the angular distances through which the dial moves during 1, 2, 3 and 4 beats, and by dividing the numbers corresponding to such distances by 360 and noting the remainders. The remainders will be found to be 90, 180, 270, and 0, and they repeat in the same order if the calculation is carried out for 5, 6, 7 and 8 beats. This means that the dial gains 90 degrees per beat and that any indicator will reappear at the same point on every fourth beat. That is, in timing a six-beat watch the indicator in use reaches the same position on every fourth beat instead of on every second beat as is the case in timing a five-beat watch.

The dial may be rotated at a speed of 2½ R. P. S., or 180 degrees per beat, with satisfactory results. This is a rather low scanning speed, however, and the advantage of being able to time six-beat watches as well as five-beat watches is not obtained. The next speed above 7½ R. P. S. which might be considered is 12½ R. P. S., but would be too high for use in most cases. I prefer, therefore, to use a dial speed of 7½ R. P. S., although the invention is not necessarily limited to this particular speed.

The invention having been described, that which is believed to be new and for which the protection of Letters Patent is desired will be pointed out in the appended claims.

I claim:

1. In a timing apparatus, a panel having two oppositely disposed arcuate windows therein, a

rotatable dial behind said panel, said dial being effective to close said windows except for exposure thereof by an opening in said dial which moves successively past said windows when the dial is rotated, two lamps located behind said dial opposite said windows, respectively, means responsive to the beating of a watch for flashing said lamps simultaneously, and means for rotating said dial at a constant speed such that if said opening is passing one window when illuminated by one lamp flash it passes the other window as it is illuminated by the next successive lamp flash.

2. In a timing apparatus, a rotatable dial having two indicators spaced 90 degrees apart, two scales associated with said indicators having their zero points spaced 90 degrees apart, means for illuminating said indicators responsive to the beating of a watch, and means for rotating said dial at a constant speed such that any two successive lamp flashes display said indicators, respectively, one at one of said scales and the other at the other of said scales.

3. In a timing apparatus, a rotatable dial having two indicators spaced 90 degrees apart, two scales associated with said indicators having their zero points spaced 90 degrees apart, means for illuminating said indicators responsive to the beating of a watch, means for rotating said dial at a constant speed such that every alternate watch beat is effective to display said indicators simultaneously at corresponding points on said scales, respectively, and means for changing the phase relation between the dial and watch beats, whereby two successive watch beats are effective to display said indicators alternately, one indicator being displayed at one scale and the other indicator being displayed at the corresponding point on the other scale.

4. In an apparatus for timing watches and the like, a panel having two arcuate windows therein, lighting means behind said panel, means responsive to each beat of a watch being timed for causing said lighting means to emit a flash of light directed substantially equally toward said windows, and a rotatable element interposed between said panel and lighting means, said element including means effective, when the element is rotated at a suitable speed, to cause alternate light flashes to be visible at a first one of said windows but not at the second and the intervening light flashes to be visible at the second window but not at the first.

5. In an apparatus for timing watches and the like, a panel having two arcuate windows therein, two lamps behind said panel for illuminating said windows, respectively, means for flashing both lamps responsive to each beat of a watch being timed, a rotatable element located between said panel and lamps and adapted when rotated to close said windows alternately to the passage of light, while admitting light to each window at a time when the other window is closed, and means for rotating said element at a constant speed such that one window passes light from the flashes produced by the odd beats of the watch while the other window passes light from the flashes produced by the even beats.

6. In a timing apparatus, a panel having two concentric arcuate windows therein, lighting means behind said panel common to said windows, means responsive to each beat of a watch being timed for causing said lighting means to emit a flash of light directed substantially equally

toward both said windows, a rotatable dial interposed between said panel and lighting means and operative to render any given light flash visible at only one of said windows, said dial having two openings spaced 180 degrees apart and located at different distances from the rotation axis of the dial to enable them to cooperate with said windows, respectively, and means for rotating said element at a constant speed such that if a given light flash is visible at one window through the associated opening the next succeeding light flash will be visible at the other window through its associated opening.

7. In a watch timing apparatus, a rotatable dial having a single opening therein, means located in front of said dial and bearing two fixed reference indicators thereon for cooperation with said opening, said indicators being spaced around the rotation axis of said dial by 180 degrees, means for rotating said dial at a constant speed such that the dial makes a net gain of 180 degrees per beat of the watch being timed, whereby the opening in said dial is associated with one of said indicators on alternate watch beats and with the other indicator on the intervening beats, and means located behind said dial and responsive to each successive watch beat for producing a flash of light directed

substantially equally toward said reference indicators, the said dial being effective to prevent the illumination of each indicator by light flashes occurring at times when the said opening is associated with the other indicator.

8. In a watch timing apparatus, a rotatable dial having two openings therein, said openings being spaced around the rotation axis of said dial by 180 degrees and being located at different distances from said axis, means located in front of said dial and bearing two reference indicators located at different distances from said rotation axis and associated with said openings, respectively, said indicators being in radial alignment, means for rotating said dial at a constant speed such that the dial makes a net gain of 180 degrees per beat of the watch being timed, whereby said dial openings pass their respective indicators alternately, and means located behind said dial and responsive to each successive watch beat for producing a flash of light directed substantially equally toward said reference indicators, the said dial being effective to prevent the illumination of each indicator by light flashes occurring at times when the other indicator is being passed by its associated dial opening.

RODNEY G. RICHARDSON.
